his Attorney.

UNITED STATES PATENT OFFICE.

HARRY W. YOUNG, OF CHICAGO, ILLINOIS

FUSE-HOLDER.

1,095,135.

Specification of Letters Patent. Patented Apr. 28, 1914.

Application filed January 10, 1913. Serial No. 741,171.

To all whom it may concern:

Be it known that I, HARRY W. YOUNG, a citizen of the United States, and a resident of the city of Chicago, county of Cook, and State of Illinois, have invented certain new and useful Improvements in Fuse-Holders, of which the following is a specification.

My invention relates to improvements in fuse holders and has for its object the provision of an improved holder for electrical blow-out fuses which is of simple construction and efficient in use.

A further object of the invention is the provision of an electrical fuse holder which can only be used when fully assembled.

The invention consists in the combinations and arrangements of parts hereinafter described and claimed.

The invention will be best understood by reference to the accompanying drawings forming a part of this specification, and in which,

Figure 1 is a side elevation of a fuse holder embodying my invention, Fig. 2, a longitudinal section of the same, Fig. 3, a view of an interior tube employed in the construction showing the end cap thereon in section, and Fig. 4, a detail view of an outer tube employed in the construction showing the end cap thereon in section.

The preferred form of construction as illustrated in the drawings comprises outer and inner tubes 1 and 2 made of fiber or other suitable insulating material and of a size to snugly telescope with each other as shown in Fig. 2. One end of outer tube 1 is closed by a metallic cap 3 which is secured thereover as shown. The opposite end of tube 2 is closed by an end cap 4 which is of a size to fit snugly over the corresponding end of tube 1 as indicated in Fig. 2. End caps 3 and 4 serve to close the ends of tubes 1 and 2 and also constitute the line terminals of the fuse as will be readily understood by those skilled in the art.

A metallic clamping member 5 is secured in each end of inner tube 2 and is provided with a co-operating clamping plate 6 and clamping screw 7 for clamping the ends of fuse member 8 in position as indicated in Fig. 2.

The cap 4, terminal 5 and inner tube 2 may be riveted together in the manner shown by inserting a suitable tool through opening 13 to hold the heads of the rivets as will be readily understood.

End cap 3 is provided with a contact screw 9 threaded therethrough and adapted to contact with the corresponding clamping member 5 to effect electrical connection between said end cap and said clamping member when the tubes are assembled as indicated in Fig. 2. Tube 2 is provided with a slot 10 which is zigzag in shape at its central portions but straight at its end portions 11 so as to permit the insertion of fuse member 8 therein, which is made zigzag to fit said slot, said tube being also provided with openings 12 and 13 adapted to give access to the clamping screw 7 when tube 2 is withdrawn from tube 1, end cap 4 being provided with an opening 14 registering with opening 13 for this purpose.

In the construction set forth, it will be noted, that the fuse member will be entirely inclosed and protected and that the parts may be readily separated or put together in replacing fuse members. By placing an end cap on each of the separable tubes it is rendered necessary to fully assemble the holder before the same can be used and the separation and assembling of parts is greatly facilitated. It will also be noted that the fuse member employed must be properly shaped to pass through slot 10, so that by giving slot 10 different forms for fuses of different capacities and making the corresponding fuse members to fit the corresponding slots only mistakes or tampering with the fuse are prevented.

While I have illustrated and described the preferred form of construction for carrying my invention into effect this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A device of the class described comprising two longitudinally separable telescoping tubes constituting a fuse casing, one of said tubes being of a size to fit snugly within the other for substantially its entire length; a terminal contact member carried by each of said tubes but at opposite ends thereof; and a fuse member electrically connected with said contacts, substantially as described.

2. A device of the class described comprising two separable telescoping tubes constituting a fuse casing, one of said tubes being of a size to fit snugly within the other for 5 substantially its entire length and provided with a slot therein adapted to permit insertion of a fuse member; a terminal contact member carried by each of said tubes; a fuse member of the same shape as and adapted to 10 be inserted through said slot; clamping members in each end of the inner tube adapted to clamp said fuse member; and electrical connections between said clamping members and said contacts, substantially as 15 described.
3. A device of the class described comprising two separable telescoping tubes constituting a fuse casing, one of said tubes being of a size to fit snugly within the other for 20 substantially its entire length and provided with a slot of distinctive shape adapted to permit the insertion of a fuse member; a terminal contact member carried by each of said tubes; a fuse member of the same shape 25 as and adapted to be inserted through said slot; clamping members in each end of the inner tube adapted to clamp said fuse member; and electrical connections between said clamping members and said contacts, substantially as 30 described.
4. A device of the class described comprising two separable telescoping insulating tubes constituting a fuse casing; a metallic cap secured over one end of the inner tube 35 and of a size to pass over the corresponding end of the outer tube; a metallic cap secured over the other end of the outer tube; and a fuse member electrically connected with said caps, substantially as described.
- 40 5. A device of the class described comprising two separable telescoping insulating tubes constituting a fuse casing; a metallic cap secured over one end of the inner tube and of a size to pass over the corresponding 45 end of the outer tube; a metallic cap secured over the other end of the outer tube; a metallic clamping member secured in each end of said inner tube, the clamping member in the corresponding end of said tube being electrically connected with the cap thereon; means for effecting an electrical connection 50

between the cap on the outer tube and the other clamping member; and a fuse member connected between said clamping members, substantially as described.

55

6. A device of the class described comprising two separable telescoping insulating tubes constituting a fuse casing; a metallic cap secured over one end of the inner tube and of a size to pass over the corresponding 60 end of the outer tube; a metallic cap secured over the other end of the outer tube; a metallic clamping member secured in each end of said inner tube, the clamping member in the corresponding end of 65 said tube being electrically connected with the cap thereon, and there being openings in the walls of said inner tube giving access to said clamping members; means for effecting electrical connection between the 70 cap on the outer tube and the other clamping member when said tubes are assembled; and a fuse member connected between said clamping members, substantially as described.

75

7. A device of the class described comprising a casing provided with a slot extending substantially the full effective length of the tube and having a distinctive shape in its central portion but plain at its ends; clamping means in said casing adapted to clamp the ends of a fuse member; and a fuse member shaped to pass through said slot and engage said clamping means, substantially as described.

85

8. A device of the class described comprising a casing provided with a slot extending substantially the full effective length of the tube and having a zig-zag shape in its central portion but plain at its ends; clamping 90 means in said casing adapted to clamp the ends of a fuse member; and a fuse member shaped to pass through said slot and engage said clamping means, substantially as described.

95

In testimony whereof I have signed my name to this specification in the presence of two subscribing witnesses.

HARRY W. YOUNG.
